UNITED STATES PATENT OFFICE.

CHARLES FRECH, OF STEELTON, ONTARIO, CANADA.

AUTOMATIC VALVE.

1,270,282.

Specification of Letters Patent. Patented June 25, 1918.

Application filed December 15, 1916. Serial No. 137,227.

To all whom it may concern:

Be it known that I, CHARLES FRECH, a subject of the King of Great Britain, and a resident of Steelton, District of Algonia, Province of Ontario, and Dominion of Canada, have invented a certain new and useful Improvement in Automatic Valves, of which the following is a specification.

My present invention relates to valves and 10 more particularly to that class which operate automatically and are technically classed as force-closed mechanisms.

It is now common practice to embody in blowing engines, air compressors, and other 15 machines, intake or discharge valves, or both, which are mechanically operated, as by positive gear. These valves when in use become a source of annoyance, since one or more of the parts frequently become broken, 20 rendering the positive gear inoperative. Furthermore, the mechanism for mechanically operating the valves of a single machine, in many instances, is of considerable weight, which makes the initial cost high, 25 rendering assemblage expensive, and makes the cost of transportation, installation, foundations, etc., expensive.

The principal objects of my invention are therefore, first, to provide valves for blowing engines, air compressors, and other machines, which are compact, relatively light, in weight, consistent with durability, and easily assembled into operative relation to existing machines; second, valves embodying mechanism which may be either used 30 for controlling intake or discharge of fluid; third, valves embodying flaps so mounted as to accommodate themselves to the port-contained member to effectively close the port 35 when acted upon by suction or compression, and which are normally but yieldably held in a closing position by spring action; and, fourth, valves embodying parts which may be easily adjusted and replaced when worn 40 or broken.

Other objects of my invention will appear in the following detailed description, taken in connection with the accompanying drawings, forming a part of this specification, 45 and in which drawings:

Figure 1 is an end elevation of a valve embodying my invention.

Fig. 2 is a side elevation of the same.

Fig. 3 is a view of the opposite end of the valve. 55

Fig. 4 is an enlarged sectional view on the line 4—4 of Fig. 1.

Fig. 5 is a sectional view on the line 5—5 of Fig. 4.

Fig. 6 is a perspective view of a flap for 60 controlling ports of the valve, and a portion of its supporting mechanism.

Fig. 7 is a perspective view of another portion of the supporting mechanism of the flap. 65

Fig. 8 is a view partly in elevation and partly in central vertical section through a blowing tube, disclosing means for retaining the valve in operative relation thereto, and is one example of the application of my invention to machines. 70

In the drawings, where similar characters refer to similar parts throughout the several views, A designates a valve drum provided with ports B; C flaps for controlling the 75 ports B; D means for movably mounting flaps C independently one of another and yieldably holding them seated; E means limiting the amplitude of movement of said flaps away from their seats; and F, a blowing tube showing one application of my valve to machines. 80

Referring first to the drum A, the major portion 9 is preferably polygonal in cross section, as clearly shown in Fig. 5 of the 85 drawing, presenting a plurality of flat faces 10 at the periphery of the drum and about which extends an annular flange 11 provided with a beveled face 12, adapted to seat itself against a portion of the machine in which 90 the valve is used, as hereinafter more fully set forth.

The ports B open at the faces 10, lead from the interior of the drum, these ports being preferably elongated and extending 95 axially of the drum as is clearly shown in Fig. 4 of the drawings, it being preferred to provide two ports open to each face 10. The drum is open at one end at the flanged portion, and is provided with a head 13 at 100 its other end portion, said head being preferably pyramidal and extending to the interior of the major portion 9. When in this shape, the head has the dual function of closing one end portion of the drum against 105 the passage of fluid, when in use, and also

deflecting fluid discharged through the valve toward the ports B. To strengthen the drum and divide the fluid to be discharged, a plurality of webs 14 are provided 5 between the head 13 and the internal periphery of major portion 9, said webs being radially disposed with respect to the axis of the valve. If desired, the head 13 may be provided with a screw-threaded aperture 15 10 at its apex portion to facilitate handling and into which the end portion of a retaining device, hereinafter more fully set forth, may enter.

In the example shown, the flaps C are 15 formed from flat strips of metal, preferably vanadium steel, and are provided with transverse ways 16 extending longitudinally of the flaps, each flap provided with a reduced end portion or stem 17, as is clearly 20 shown in Fig. 6 of the drawings. One flap is provided for each face 10 of the drum, and when seated against said face, closes the ports B open thereto, against passage of fluid from the exterior of the valve to the 25 interior thereof, the ways 16 of the flaps C offset with respect to the ports B, as is clearly shown in Fig. 5 of the drawings.

Referring now to the means E for removably mounting the flaps C independently 30 one of another, and yieldably holding them seated, such may comprise a support 18, such as a yoke carried by drum A,—one support for each flap C; and, a coil spring 19 having its inner end portion detachably 35 connected with support 18 and its outer end portion operatively connected with its respective flap C. The support or yoke 18 may be detachably carried by the drum A as by being provided with a stem 19', which extends 40 through a slot 20 in a boss 21 rigid with the head 13, said boss provided with a screw-threaded aperture 22 in which a set-screw 23 has engagement, the set-screw being turned tight against stem 19' to hold 45 the support or yoke in a rigid adjusted position. Arms 24 of yoke 18 may be provided with annular bosses 25 which confront one another, and engage the inner end portion 50 of the spring 19 as is clearly shown in Fig. 4 of the drawing, each arm 24 provided with an offset 26, perforated as at 27 through which a pin 28 extends, and against which an angular portion 29 of the spring 19 abuts in a manner to place the fiber of the spring 55 under compression. The outer end portion of the spring may be operatively secured to the flap as by rivets 30, one or more of which may extend through the stem 17 of the flap. It is to be observed that the spring 60 19 yieldably forces the flap into engagement with its respective face 10 of the drum A, and that by moving the support 18 with respect to the body A, adjustment may be obtained so that there will be surface contact 65 between the flap and the face of body A.

If, for any reason, there should not be surface contact as the result of this spring action, it is to be observed that, if there is suction within the body A, the spring 19 will yield to permit the flap to move into surface 70 contact, or, if there is compression acting upon the outer face of the flap, said spring will yield to permit of surface contact between the flap and its seat, the function of the spring 19 being to primarily move the 75 flap toward the body A when the ports are to be closed, and rendering the valve quick in action. The bosses 25 of arms 24 may be drawn into intimate contact with the inner end portion of the spring 19 as by 80 bolts 31, extending transversely through perforations 32 in arms 24, and nuts 33 turned tight upon said bolts.

As suitable means for limiting the amplitude of movement of the flaps C away from 85 their seats, one or more angle-strips 34 may be provided adjacent each flap, in the example shown, two such angle-strips being provided for each flap. One end portion of one leg of each strip may be secured to the 90 drum A as by screw 35, extending through the end portion and in screw-threaded engagement with a lug 36 which may be cast integral with major portion 9 as is clearly 95 shown in Figs. 2 and 4 of the drawings, the other leg of the strip being secured to the end of the drum as by machine-screw 36', in a manner that a face 37 of the strip confronts the flap C, but is in angular relation to the face 10 against which the valve seats 100 itself. This angular relation is such that, when the flap moves away from the drum A, without placing the spring 19 under undue tension, the flap will engage the said face 37 with surface contact. Thus, even though 105 the valve be used for a considerable length of time, its vibration to and from the strips 34 will not tend to displace it with respect to the spring 19 after adjustment has been obtained. If the face 37 of strip 34 were in 110 parallel relation to the face 10, then the free end portion of the flap would first engage the strip 34 and the action of fluid upon the face of the flap normally engaging the drum A, would tend to displace the convolutions 115 of the spring 19 and under some conditions, might result in the permanent set of the spring so that it would not primarily seat the flap C with surface contact, as hereinbefore described.

In assembling the valve in operative relation for the control of fluid, by way of example, I have shown the relative position of the drum of the valve in operative relation to a blowing tube, in which the bodies 40, 125 disposed in spaced relation, provide a passage-way 41 for fluid, the body having apertures 42 and 43 in opposite walls, 44, and 45, respectively, the wall 44 being a part of a cylindrical extension 46 about which one end 130

- portion of a cylinder 47 slides, the end portions of said cylinder being provided with a plurality of perforations 48 for ingress of air to the interior of the cylinder. A piston 49 is reciprocable in cylinder 47 as through rod 50. The valves in this instance, are to prevent ingress of fluid from passage-way 41 to the interior of cylinder 47, and are disposed with their flanges 11 engaging the 5 wall 44, with the open end of the drum open to aperture 42. The valves are held in place as by a bolt 51 in screw-threaded engagement with a plate 52 secured in a manner to close aperture 43, the end portion of bolt 10 51 being in engagement with head 13 of the drum, and, in the example shown, at the apex portion of said head. A set-nut 53 is provided on bolt 51, turned tight against plate 52. The aperture 43 is of a size to permit 15 the valve to pass entirely through the same, and, after the plate 52 has been secured in place, the bolt 51 is turned tight so that the flange 11 of the drum is in fluid-tight engagement with the wall 44. As the 20 piston 49 moves in the direction indicated by arrow in Fig. 8, air is forced through ways B of the valve, forcing the flaps C into engagement with the strips 34, the air finding egress from the valve through ports B at all 25 sides of the flaps and through the ways 16 of the flaps. Before the piston moves in a counter direction, the cylinder 47 is moved so that the perforations 48 provide for intake during the return stroke of the piston. 30
- 35 In the example shown, the valves are therefore used to provide for the discharge of fluid compressed by the piston. They may, however, be used to provide for intake of fluid as by passing the major portion of the 40 drum A through aperture 42 with flange 11 engaging the wall 44, under which condition the end portion of bolt 51, which may be tapered, enters the aperture 15 in head 13, forcing the flange 11 into intimate contact 45 with wall 44, said flange being shaped so as to prevent passage of fluid thereby.
- Changes in details may be made without departing from the spirit or scope of my invention; but,
- 50 I claim:—
1. In an automatic valve, a valve drum with its major portion polygonal in cross section and having ports leading from its interior and open at the faces of the major portion, flaps for controlling the passage of fluid through said ports, coil springs connected to said flaps for yieldably holding them in position, adjustable means for regulating the tension of said springs and connecting said springs to said valve drum whereby limited longitudinal adjusted movement of the said flaps is permitted.
  2. In an automatic valve, a valve drum with its major portion polygonal in cross section and having ports leading from its 55 section and having ports leading from its 60 65
- interior and open at the faces of the major portion, flaps for controlling the passage of fluid through the said ports, yokes adjustably connected to said drum, coil springs carried by said yokes and connected to said flaps, whereby limited adjusted movement of said flaps is permitted. 70
3. In an automatic valve, a valve drum with its major portion polygonal in cross section and having ports leading from its 75 interior and open at the faces of the major portion, flaps for controlling the passage of fluid through said ports, said flaps provided with longitudinal openings which are out of alignment with said ports and permit 80 passage of fluid through the flaps when they are in an outward position, coil springs connected to said flaps for yieldably holding them in engagement with the faces of the major portion, adjustable means for adjusting the tension of said springs and connecting said springs to said valve drum whereby limited longitudinal adjusted movement of said flaps is permitted. 85
4. In an automatic valve, a valve drum 90 with its major portion polygonal in cross section, each of the faces of said major portion provided with a pair of spaced ports leading from the interior of the drum, a flap for controlling the passage of fluid through 95 each pair of said ports, said flap provided with a longitudinal opening positioned between the ports, coil springs connected to said flaps for yieldably holding them in position, and adjustable means connecting said 100 springs to said valve drum whereby limited longitudinal adjusted movement of the said flaps is permitted.
5. In an automatic valve, a valve drum with its major portion polygonal in cross 105 section and having ports leading from its interior and open at the faces of the major portion, flaps for controlling the passage of fluid through said ports, yokes adjustably connected to said drum, coil springs carried 110 by said yokes and connected to said flaps, and means carried by said yokes to hold the fiber of the springs under tension.
6. In an automatic valve, a valve drum with its major portion polygonal in cross 115 section, each of the faces of said major portion provided with a pair of spaced ports leading from the interior of the drum, a flap for controlling the passage of fluid through each pair of said ports, said flap provided 120 with a longitudinal opening positioned between the ports, yokes adjustably connected to said drum, coil springs carried by said yokes and connected to said flaps, and means carried by said yokes to hold the fiber of 125 the springs under tension.
7. In an automatic valve, a valve drum with its major portion polygonal in cross section, each of the faces of the said major portion provided with a pair of spaced 130

ports leading from the interior of the drum, a flap for controlling the passage of fluid through each pair of said ports, said flap provided with a longitudinal opening positioned between the ports, yokes adjustably connected to said drum, coil springs carried by said yokes and connected to said flaps, and means carried by said yokes to hold the

fiber of the springs under tension, straps attached to said drum for limiting the amplitude of movement of said flaps, the inner faces of said straps confronting said flaps near the edges of the flaps and at an angle to the faces of the drum. 10

CHARLES FRECH.
